WILLIAM V. HEINZ, OF LA SALLE, ILLINOIS.

METAL BEAD FOR PLASTERINGS.

1,111,153.

Specification of Letters Patent.

Patented Sept. 22, 1914.

Application filed March 11, 1912. Serial No. 682,960.

To all whom it may concern:

Be it known that I, WILLIAM V. HEINZ, of La Salle, in the county of La Salle and State of Illinois, have invented certain new and useful Improvements in Metal Beads for Plasterings, of which the following is a specification.

My invention relates to sheet metal beads such as are applied usually for protecting the salient corners of the plaster walls; and the chief object of my improvements is to provide a sheet metal bead which can be applied not only for protection to corners of different angles but also to level surfaces to serve as a line of division between different kinds of plaster laid on such surfaces. I attain this object by the means illustrated in the accompanying drawings, in which—

Figure 1 is an elevation showing my improved bead as applied to a square corner, the lower portion of which is of brick and the upper part frame, without the plaster. Fig. 2 is a cross section cut squarely across the bead as arranged for a square corner, the dotted lines showing the extreme position to which the side parts may be turned apart in order to fit a straight or level surface instead of a corner. Fig. 3 is a similar view to Fig. 2 but shows a modification of the front part designed for two-coat work, the side parts being turned apart to fit a corner having an obtuse angle, and the dotted lines indicating the depth of the ground and finishing coats of plaster, as applied thereto. Fig. 4 is a detail showing a perspective view of the front part detached from the side parts. Fig. 5 is a detail showing, in perspective, the modified form of the front part, detached. Fig. 6 is a horizontal section showing some additional bends in the side pieces.

Similar letters refer to similar parts throughout the several views.

My improved bead comprises duplicate sheet-metal side parts designated generally by A A and designed to be secured together and to the wall and to be embedded or covered with the coat of plaster, and an exposed outer part, or nose-piece B (the bead proper) to be attached to the embedded parts; so as to hold them together and stand out exposed to view at the corner or surface of the plaster.

The parts A A are formed, each, of a straight strip of galvanized iron about one and a half inches wide and of any desired

length with a longitudinal bend at a near one edge leaving a marginal flange a¹ of about one eighth inch extended preferably at right angles and running the entire length of the strip. At about a half inch from the bend a and parallel therewith is another bend a² at a preferred angle of about 45 degrees, and leaving the remainder of the strip A flat. This flat part is designed to fit against the wall and is provided with nail holes or slots a³ preferably extended diagonally of the strip so as to cross the mortar joints of brick walls, and facilitate the nailing into them for securing the parts A A to the wall.

That part of the strips which is between the bends a and a² is designed to form the support proper for the bead B and is provided with a series of slots a⁴ each of which extends from one of said bends to the other and through which rivets or screw bolts C may be applied for holding the parts A A together when on a corner of the wall. Light wire strung through these openings obviously might be used instead of the bolts to tie said parts together, or solder might be used. It is noted that when the parts between the bends a a² are brought together in parallel relation the remaining wider parts of A A having the nail holes, are extended at right angles as seen in Fig. 2 (full lines), and the tie bolts C are located and tightened at the end of the slots a⁴ adjacent to the bend a². When a greater angle is desired the bolts are loosened as seen in Fig. 3. Said bolts are movable along the slots a⁴ so that when a further increase of the corner angle is desired it may be secured by moving the tie bolts in said slots toward the bend a and tightening or loosening them so as to keep the duplicate parts in contact at the bends a as seen in dotted lines Fig. 2.

Plaster openings a⁵ are made at frequent intervals through which the plastic mortar passes so as to fill the open space between the parts down to the bends a², which, when hardened, will keep the tie bolts firmly in place.

In Fig. 6 the side strips are shown as being slightly corrugated at a⁶, a⁷, the object being to increase the rigidity to the strips; also to permit the plaster to take hold under the flat pieces which will produce additional anchorage for the plaster.

The exposed bead B may be of superior material. It is formed of a narrow strip

of sheet metal rolled to tubular shape leaving a longitudinal slot b its entire length, the width of the slot corresponding to the thickness of the double layers of the sheet metal of which the duplicate parts A A are made. I do not wish to be understood as limiting myself to the rivets or screw bolts C for holding these parts together as the fastening may obviously be varied in many well known ways without departing from my invention. The cross-sectional interior shape of said part B is such as to slide over the marginal flanges a^1 and engage below the same in order to hold said part B in place on its support, and also to permit the flanges a^1 to rotate in the interior of part B, opposite the slot b , in compensation for the spreading of the parts A from the angles shown in full lines to the angles shown in dotted lines, Fig. 2.

When the parts A A are used on a frame structure of wood they may be sufficiently secured by means of nails driven into the frame through the slots a^3 , or ordinary holes, but when they are used on a brick wall the nails must be driven into the mortar joints c and in order to hit such joints readily the slots a^3 are extended diagonally and lap by each other so as to form practically a continuous nail hole throughout the length of the bead which shall cross the mortar joints at a sufficient number of points to afford a secure fastening.

It often happens in fastening the parts to a corner of brick by nailing through the diagonal slots said slot will cross the mortar joints too near the corner to afford a good holding. In such case I use clips D (Fig. 1) which are each formed of a strip of galvanized sheet iron provided with nail holes c^1 and having their opposite ends folded on diagonal lines d , corresponding with the incline of the slots a^3 , so that the fold d^1 may be hooked through said diagonal slots a^3 and adjusted therein so as to bring some one of the nail holes c^1 in line with a mortar joint c. The folds d^1 are provided at both ends of the clips so that any clip is thereby made applicable on either side of the brick wall corner wherever a defective nailing place may occur.

When the parts are assembled and mounted on a corner, as shown in Fig. 1, the bead B is adapted to stand firmly in place and serve as a guide to the workman when spreading the mortar, enabling him to lay a straight even coat at both sides of the corner, first on one side and then on the other, without waiting for the first side to dry. The coat should lie parallel with the opposite sides of the corner and have sufficient thickness to cover the parts between the bends a and a^2 as indicated by the dotted lines Fig. 1, which show the location of the lines of the outer surface of the plaster coat

at opposite sides of the corner. The plaster fills the entire space under the bead B and joins the bead without forming a feather-edge so thin as to be liable to break off.

When the parts A A are turned out, to the position shown by dotted lines Fig. 2, the bead B will lie on the surface of the plaster and may run horizontally and serve as a line marking off a dado.

In the modification, B¹ is formed with a longitudinal crease B² which forms a guide for the laying of a ground coat E (Fig. 3) of uniform thickness upon which a finishing or second coat e may be laid, the plasterer working from the part of the bead which is outside of said crease in determining the thickness of the finishing coat.

It is noted that the form of the parts A A and B is such that they can be very cheaply manufactured and applied as well to any angle of corner as to a level surface, that the outer margins of the parts A A are adapted to be nailed either to a wooden or a brick wall surface and that the opposite or inner margins a^1 are adapted to engage the part B or B¹ through the slot b or b^1 so that the inner margins will be held together and secure the said parts A A and B or B¹ in the several working relations shown and described.

I am aware that prior to my invention metal beads for plastering have been made with a strip of sheet metal so shaped as to present at its mid-width a tube or channel having their outer edges inturned and forming auxiliary flanges resulting in the production of a triangular space along said channel to receive the head of a clip attached to the wall for attaching the bead to a corner. Also a prior similar form in which the flanges or walls diverging from the channel were outturned instead of inturned. I therefore do not claim such a combination broadly; but

I claim:

1. In a metal bead of the class described, oppositely arranged duplicate parts A, A, placed in juxtaposed relation to each other, each part having at one edge a right angular flange, the flanges of adjacent parts being oppositely extended, opposite longitudinal bends a^2 at an angle of about forty-five degrees and opposite flat parts provided with nail holes, in combination with a tubular bead B provided with a longitudinal slot adapted to receive the flanged edges of said parts A A and permit rotation of each in said slot in opposite directions through an arc of about forty-five degrees.

2. In a metal bead of the class described, separate duplicate parts A, A, placed in juxtaposed relation to each other, each part having at one edge a right angular flange, the flanges of adjacent parts being oppo-

sitely extended, longitudinal bends a^2 , diagonal slots a^3 , spaced apart on one side of said longitudinal bends and transverse slots a^4 , on the opposite side of said longitudinal bends, and adapted to match one another on the opposite sides of a corner, means for attaching said separate parts together on a corner and a semi-cylindrical tubular bead B provided with a continuous longitudinal slot in its flat side adapted to receive said marginal flanges and slide on the same, its flat side facing toward the wall.

3. In a metal bead of the class described, the opposite duplicate parts A, A, placed in juxtaposed relation to each other, each part having at one edge a right angular flange, the flanges of adjacent parts being oppositely extended, and the slotted tubular part B adapted to slide upon said marginal flanges for securing said parts together in the manner described and permitting said marginal flanges to be rotated in said part B for varying the position of said parts A, A, relatively to the wall to any angle from right angle to a straight line.

4. In a metal bead of the class described, and in combination, duplicate parts A, A,

provided with marginal flanges a^1 , a^1 , placed in juxtaposed relation to each other, and diagonal slots a^3 spaced apart and arranged 30 in a row extending longitudinally of said parts, means for connecting said parts together below said marginal flanges, a clip D provided with diagonal folds d^1 at its ends to match the inclination of the diagonal 35 slots a^3 , and the slotted tubular part B, adapted to slide upon said marginal flanges for securing said parts together in the manner described.

5. In a device of the class described, a 40 tubular bead having an open seam extending the length thereof, a pair of pliant sheet metal wings, each wing having at one of its side margins an integral flange extending throughout the length of the wing, which 45 flanges fit within the bead and the wings extend outwardly through the seam so that the wings may be hingedly connected with the bead and the bead be reinforced throughout its length by said flanges.
